FLOWER HOLDER

Howard A. Post, Oakland, Calif.

Application October 22, 1941, Serial No. 416,008

2 Claims. (Cl. 24—6)

This invention relates to improvements in flower holders and more particularly to flower holders for personal adornment.

Among the objects of the invention is the provision of a simple inexpensive and decorative means for effectively holding a small bouquet or a single flower attached to a garment.

Another object is to so design and arrange the parts of the invention that it may be made of a single piece of relatively thin sheet material, having attaching means thereon.

Other objects and advantages will appear as the description progresses.

In this specification and the accompanying drawing, the invention is described in its preferred form. But it is to be understood that it is not limited to this form; because it may be embodied in modifications within the spirit of the invention as defined in the claims following the description.

In the one sheet of drawings:

Figure 1 is a plan view from above of a flower holder constructed in accordance with this invention.

Fig. 2 is a side view of the same, partially broken away in vertical section.

Fig. 3 is a rear view of the same partially broken away at the top.

Fig. 4 is a plane view of the blank from which the body of the holder is formed.

Fig. 5 is a modification of the same shown in vertical section.

In detail the construction illustrated in the drawing, referring first to Fig. 2, comprises the front 1, with the integral clamp jaw 2, folded backwardly at 3, over the rear plane of the front 1. The sides 4, 5 are integral with the front and are folded backwardly at 6, 7, and 8, 9, so that the rear panels 10, 11 overlap the desired distance, see Fig. 3. These panels 10, 11 are cemented together at 10' and form the rigid back of the tubular body against which the jaw 2 bears with the necessary resilient tension to hold the stem of the flowers forced therebetween from above.

The rear panel 11, is cut away adjacent its upper edge, see broken away portion in Fig. 3, to receive the attaching pin 12. This attaching pin has the sharpened end adapted to engage beneath the keeper 13 that is formed by flattening the opposite end of the pin. The body of the pin intermediate its ends is provided with the hump 14, that lies within the cutaway portion 15 of the panel 11, see Fig. 3.

The inner panel 10, has the upward extension

16 folded rearwardly at 17 and overlying the rear plane of the panel 11 to which it is cemented at 10', to confine the hump 14 and intermediate portions of the attaching pin within the cutaway portion 15, between the inner panel 10 and the extension 16. The hump 14 prevents the pin from turning and maintains the plane of the pin perpendicular to the plane of the panel 11.

Because of the choice of attractive color schemes, modern sheet plastics are desirable for blanking and forming in accordance with this invention, bearing in mind the tension necessary in the clamping jaw 2. If sheet metal is preferred it is equally adaptable by substituting spot welding or soldering at 10' or by depending upon the natural stiffness of the material to maintain the tubular shape.

The invention operates substantially as follows: The pin 12 is unhooked from the guard 20 and inserted in the fabric of the garment of the wearer, then the pointed end is reinserted in the guard in the usual manner. The stem of the flower or the bouquet is then forced into the top opening of the holder and downwardly until 25 the stem is clamped securely between the jaw 2 and the inner plane of the panel 10.

Any decorative object, such as a flag, fraternal emblem or the like, such as 18, can be attached to the front 1.

30 Fig. 5, shows a modification of structure, in which the ends of the blank of sheet material are not fully overlapped. The front panel 1x has the two sides such as 4x, and the rear panel 10x, with the end 11x cemented thereto laterally to the vertical center. These ends could abut in the same plane. This form is especially adaptable to the use of metal or stiff material requiring no soldering or cementing of the ends of the panels 10x, 11x.

35 The spring jaw 2x is formed integrally with the rear panel 10x and bears against the rear plane of the front panel 1x. The pivot 18 and the keeper 19 have the lugs 20, 21, respectively, clinched through the panel 10x. The sharpened 40 pin 22 is pivoted in 18 and detachably engages the keeper 19.

45 This modified structure requires less material and lends itself better to automatic mass production. Its mode of operation is substantially the same as that previously described.

Having thus described this invention what is claimed and desired to be secured by Letters Patent is:

1. A holder of the character described, comprising a continuous sheet of material having a

Jaw portion intermediate its ends, said ends being overlapped and overlying said jaw to form a resilient clamp, one of said ends having a cutaway portion; and attaching means secured between and extending outwardly from said overlapped portion and having a part extending into said cutaway portion.

2. A holder of the character described, comprising a continuous sheet of material having a jaw portion intermediate its ends, and an exten-

sion and a cutaway portion adjacent said ends respectively, said sheet being bent upon itself to enclose and form a clamp with said jaw when said ends are overlapped behind said jaw; said extension being bent backwardly and overlapping said ends; and an attaching means lying between said extension and said ends and having a part extending into said cutaway portion.
